UNITED STATES PATENT OFFICE

WALDEMAR PETERSEN, OF BERLIN, AND RICHARD TRÖGER, OF BERLIN-ZEHLENDORF, GERMANY, ASSIGNEES TO GENERAL ELECTRIC COMPANY, A CORPORATION OF NEW YORK

STEAM GENERATING PLANT FOR THE GENERATION OF HIGH PRESSURE STEAM

Application filed April 26, 1929, Serial No. 358,319, and in Germany May 10, 1928.

A process for the generation of high pressure steam has become known in which the water in a boiler drum, already preheated, is vaporized by the introduction of superheated steam. Since losses of pressure occur in the superheater that part of the hot steam used for the heating has to be returned to the boiler by a pump. The additional pressure generated by the pump must then be so great that the pressure of the steam leaving the superheater is still sufficient to force the hot steam back into the boiler. The employment of a return pump of this kind, however, represents a disadvantage in so far as it causes considerable unsafety in the conduct of the working.

The present invention relates to a steam generating plant more particularly for the generation of high pressure steam in which, for the purpose of the vaporization, a part of the superheated steam generated in a superheater is mixed with the feed water in a jet apparatus, by which the water is vaporized, the increase of pressure produced by the mixing in the jet apparatus being utilized to effect the circulation of the mixture through the superheater. An arrangement of this kind has the advantage, compared with that above mentioned, that the disadvantageous pump is avoided. The pressure increasing effect in the jet apparatus can be controlled advantageously by regulating the pressure of the feed water.

In the drawings, Fig. 1 is a diagrammatic view of an arrangement embodying our invention, and Figs. 2 and 3 are diagrammatic views of modifications.

Our invention may be employed with advantage in combination with a vaporizing process wherein a boiler drum is utilized. Referring to the drawings, Fig. 1, 14 indicates a series of boiler drums which receive water from a feed water pump 15 through pipelines 16, 17 and 18, which are arranged in parallel and in each of which is a preheater 19, the water being heated in such preheaters preferably to the saturated steam temperature. Steam from the drums 14 is conveyed by conduits 20 through jet apparatus 21 provided according to our invention, to super-

heaters 22. From superheaters 22 a portion of the preheated steam is returned to the boiler drums by way of conduits 23 to effect vaporization of the water in the drums. The remaining portion of the superheated steam is conveyed through conduits 24 to the point or points of consumption.

Superheated steam of a pressure higher than that generated in boiler drums 14 is supplied to the jet apparatus 21 by an auxiliary or special steam generating apparatus comprising a superheater 25 to which vapor is supplied through a conduit 26 by a jet apparatus 27. Water, heated preferably to the saturated steam temperature, is supplied to the jet apparatus 27 by a separate pump 28 and a preheater 29, pump 28 being shown as being in series with the feed water pump 15. A part of the superheated steam generated in superheater 25 is fed through a conduit 30 to the jet apparatus 27, and the remainder of such superheated steam is fed to the jet apparatus 21 by the conduits 31. With the arrangement shown it will be seen that the provision of pumps for pumping steam from the boiler drums 14 to the superheaters 22 is avoided.

It will be readily understood that the superheated steam fed to the jet apparatus through conduit 31 mixes with the saturated steam fed through conduit 20 whereby the superheated steam causes an increase of pressure and thus forces the mixture of saturated and superheated steam through the superheater 22. The superheated steam supplied under pressure to the jet apparatus serves as the pumping fluid for this apparatus and the saturated steam supplied by the boiler represents the fluid to be pumped.

Instead of using separate pumps 15 and 28 we may combine these pumps into a single pump, the water being tapped off from the pumps at separate stages to give the respective pressures required. Such an arrangement is indicated in Fig. 2 wherein 32 indicates a single feed water pump which supplies the boiler drums 14 corresponding to the boiler drums 14 of Fig. 1 through a conduit 33 and which supplies the preheater 29 corresponding to the preheater 20 of Fig. 1.

through the conduit 34. Numerals 19^a indicate preheaters corresponding to the preheaters 19 of Fig. 1. Otherwise the arrangement shown in Fig. 2 may be the same as that shown in Fig. 1.

The auxiliary steam for the operation of the jet apparatus 21 shown in Fig. 1 may be taken, if desired, from any kind of known high pressure steam generating plant. Fig. 10 3 shows an embodiment of the invention which is similar to the arrangement shown in Fig. 1 except that for the generation of the auxiliary steam an apparatus is utilized comprising a boiler drum 35 from which steam 15 is supplied by a pump 36 to a superheater 37, a part of the steam from the superheater being returned by way of conduit 38 to boiler drum 35 for the purpose of generating steam therein while the remainder of the superheated steam from superheater 37 is supplied by 20 way of conduits 39 to a jet apparatus 40 corresponding to the jet apparatus 21 of Fig. 1. Otherwise the arrangement shown in Fig. 3 is similar to that shown in Fig. 1, and similar 25 reference characters, with the exponent "b" added, have been applied to the corresponding parts. In the arrangement shown in Fig. 3 the pump 36 may be of the centrifugal type.

While we have described our invention as 30 relating especially to plants for generating steam, it will be understood that it is not limited thereto necessarily but may be used to generate any other vapor.

In accordance with the provisions of the 35 patent statutes, we have described the principle of operation of our invention together with the apparatus which we now consider to represent the best embodiment thereof, but we desire to have it understood that the apparatus shown is only illustrative and that the invention may be carried out by other means.

What we claim as new and desire to secure by Letters Patent of the United States is:

1. In a vapor generating plant, the combination of a boiler drum, a pump for supplying liquid thereto, a superheater, conduit means for conveying vapor from the drum to the superheater and from the superheater to the drum, a jet apparatus in said conduit means, and an auxiliary vapor supply of higher pressure for supplying vapor to said jet apparatus.

2. In a vapor generating plant, the combination of a boiler drum, a pump for supplying liquid thereto, a superheater, conduit means for conveying vapor from the drum to the superheater and from the superheater to the drum, a jet apparatus in said conduit means, and an auxiliary vapor supply of higher pressure for supplying vapor to said jet apparatus, said auxiliary vapor supply comprising a superheater, a feed pump for supplying liquid to the superheater, a jet apparatus arranged between the pump and the

superheater, and a conduit for conveying superheated vapor to the jet apparatus.

In witness whereof, we have hereunto set our hands, this 11th day of April, 1929.
